UNITED STATES PATENT OFFICE.

EUGENE ROBERTS, OF NEW YORK, N. Y., ASSIGNOR TO THE WESTERN STATES MACHINE COMPANY, OF SALT LAKE CITY, UTAH, A CORPORATION OF UTAH.

CENTRIFUGAL APPARATUS.

Application filed November 5, 1926. Serial No. 146,433.

This invention relates to the centrifugal refining or purification of sugar or similar material, and is intended to provide a centrifugal apparatus so constructed and organized as to eliminate large losses or waste of material resulting from previous practice in this field, and at the same time to effect a great economy of labor attendance by making it practicable for an operator to attend 10 to a larger number of centrifugals, each of them operating more efficiently than under the practice heretofore prevailing.

The function of the centrifugal in sugar mills or refineries is to recover the solid 15 grains or crystals by separating therefrom both the free syrup, with which the grains are mingled, and the adhesive coating of syrup on the grains themselves. The elimination of the free syrup is effected by throwing it off centrifugally through a surrounding filtering wall constructed to retain the solid crystals in the centrifugal basket, while allowing the liquid syrup to pass through the walled-up sugar and the filter and out of 25 the perforated basket wall into a suitable collector or receptacle, all under the action of centrifugal force.

The separation of the syrup coating adhering to the crystals is effected by spraying 30 water against the walled-up sugar after the purging operation, that has extracted the free syrup, is completed.

The cycle of centrifugal operation is as follows:

35 First comes loading or charging the basket by admitting the charge of wet sugar through the delivery spout to fill the basket, rotating at low speed, to its capacity, that is, until the walled-up sugar extends from the 40 peripheral wall of the basket to about the vertical line of the inwardly overhanging cap ring or rim of the basket, which usually extends inward from the peripheral wall approximately five or six inches.

45 The second operation is purging the sugar which is effected by turning on the full power of the centrifugal drive, thus accelerating the speed as fast as the machine can pick up speed from its driving connection, 50 thus centrifugally extracting the free syrup.

Third, the washing spray is then brought into action and is directed against the inside surface of the walled-up ring of sugar through which the water is driven by cen-

trifugal force to wash off the adhesive coating of syrup on the solid sugar crystals. 55

The fourth operation is the drying of the sugar after the water is shut off by continuing the high speed of the rotation until the grains of sugar have reached the requisite 60 degree of dryness.

Fifth in order comes the braking or slowing down of the machine by the application of the brake to a low speed, permitting the discharging or unloading of the sugar. 65

Sixth comes the discharging or unloading effected by means of a suitable discharging plow which cuts down the walled up purified sugar and allows it to fall through the central outlet-opening in the bottom of the basket through which the sugar is discharged or unloaded upon a carrier which conveys it directly to the granulator. 70

Heretofore, in actual practice, all these operations, except the actual duration of the spraying or washing operation, have been controlled and directed by the operator with two very serious resultant disadvantages. In the first place, there was no uniformity or precision in determining the duration of the 75 different steps in the cycle even by the same operator, and this resulted in much waste of sugar besides producing, at times, serious trouble in the operation of the machine, often resulting in serious and sometimes fatal injury to the operator. 80

I have found, by actual test, that every pound of wash water sprayed upon the sugar-wall carries off, in solution, about three pounds of sugar. If the spray is started too 90 soon, that is, before the free syrup has been extracted, the water mingle with the syrup, thereby losing its washing efficiency and requiring the use of considerable additional water on the sugar. On the other hand, if 95 the spray be started too late the coating of syrup on the sugar crystals becomes hardened by the centrifugal drying action of the basket rotating at high speed, and thus requires the application of a larger amount of 100 water to soften this hardened coating and remove it from the sugar grains. Furthermore, if the drying operation, after washing, is continued a little too long the sugar becomes packed so hard that it may smash 105 the discharger digging into it with disastrous consequences not only to the apparatus but oftentimes to the attendant. On the other

hand, if the sugar discharged be not dry enough then, as it enters the granulator to which it is conveyed directly from the centrifugal, the excess moisture will adversely affect the granulating process which, to produce a satisfactory product, should receive the sugar at a uniform degree of dryness.

In short, there are just two operations or steps in the centrifugal cycle that can advantageously be controlled by the operator, namely, the charging or loading of the wet sugar, and in the use of a flat bottom basket the discharging or unloading of the purified sugar. As to all other steps the lack of uniformity and precision in the control exerted at will by the operator is highly wasteful and injurious, and has been a prolific source of loss and damage. Furthermore, by providing a really efficient and absolutely reliable control of all steps in the cycle, except the loading and unloading, there is effected a very substantial saving in the number of attendants required for a battery of machines, it being possible, with my improved apparatus, for the operator to care for double the number of centrifugals he has heretofore operated with far more satisfactory results in the uniform quality of the product, and in the vastly greater economy of material.

Even the operation of braking or slowing down the machine to a low enough speed to permit the use of a discharger secures a uniform duration of the braking period, since the brake shoes are set by automatically acting spring tension which can be adjusted to secure any desired uniform period of duration for this operation and a uniform speed.

Since the duration of the various operations constituting the cycle should be varied for different grades of sugar or other material, I have made simple and convenient provision for regulating or adjusting the controlling means so as to make possible such variations in the duration of any of the operations constituting the parts of the cycle to best suit the nature of the material being treated, and this also forms an important feature of my invention.

Heretofore the only practical and successful regulation and control exercised in centrifugal machine practice has been applied in practice only to regulate the duration of the washing period by such an automatically controlled washing apparatus such for example, as that set forth in United States Patent 1,224,095, issued jointly to myself and Angus H. Gibson.

I am aware that it has also been proposed to operate centrifugal machines continuously at operating speed with associated mechanism for loading, washing and unloading the continuously rotating basket, but these proposals, although suggested many years

ago, have never gone into practical use nor are they capable of practical use, partly because such continuous operation of centrifugal machines does not meet the requirements of the art and partly because, in order to effect the automatic loading and in the case of a flat bottom basket, the unloading of the basket, which is not desirable anyway, such arrangement and construction of centrifugal has been adopted as to make its operation quite impracticable for other reasons. Furthermore, none of these paper proposals or suggestions have any provision for varying the duration of such parts of the cycle of operations as they are supposed to control. For various reasons, therefore, there has not been developed any practical system or means for properly controlling and regulating the operation of centrifugal machines automatically, and I believe that I am the first in the art to provide practicable operative means for effectively accomplishing the automatic control and regulation of the various steps in the treatment of the sugar in centrifugal purification.

In general my invention comprises in combination with a gyratory centrifugal and its driving means, a starting lever operatively associated with a time-controlling mechanism, a sprayer and an automatic brake so as to determine successively the duration of the purging operation, the starting and stopping of the washing operation thereafter, the drying of the sugar for a predetermined period and the braking action for a predetermined period for the purpose of slowing down and automatically stopping the machine. My invention also consists in providing means by which the different periods of operation, from the time of charging to the time of unloading the machine, may be varied to suit the requirements of the particular grade of sugar being treated. My invention further consists in such construction and arrangement of parts as are hereinafter described and defined in the claims annexed.

In the accompanying drawings I have illustrated a specific form of construction and arrangement of the co-acting starting and controlling means embodying the principles of this invention, in association with a gyratory centrifugal machine, shown more or less diagrammatically without unnecessary illustration or description of details of construction already well understood in the art.

In the drawings

Figure 1 shows a front elevation of a suspended overhead driven gyratory centrifugal machine equipped with the apparatus for automatically controlling and timing its different operations.

Figure 2 is a side elevation on an enlarged scale at right angles to the plane of Figure

1, illustrating the construction and arrangement of the starting and stopping lever and its associated parts.

Figure 3 is a detail view in side elevation 5 of the starting lever removed from its supporting frame.

Figures 4 and 5 are detail views representing, respectively, a front elevation and a side elevation of the releasable latch or shoe 10 that prevents the return of the starting lever from high speed position during the purging, washing and drying operations.

Figure 6 is an enlarged plan view showing the main starting and stopping lever in 15 association with its actuating spring and the timer-starting connection.

Figure 7 is a plan view showing this spring and a portion of the starting and stopping lever and its interconnection with 20 the automatic brake and two-speed electric switch.

Figure 8 is a side elevation on an enlarged scale of the spraying and timing apparatus as viewed by the operator in front 25 of the machine.

Figure 9 is a front elevation of the same in a plane at right angles to Figure 8.

Figure 10 is an elevation of the spraying and timing mechanism as seen from the 30 opposite side to that shown in Figure 8.

Figure 11 is a central vertical section of the timer-actuating clutch and the timer wheels as viewed from the rear or in the opposite direction to the view of Figure 10.

Figure 12 is a detail sectional view in a 35 plane at right angles to Figure 11 through the clutch-shift.

Figure 13 is a plan view of the sprayer and timer.

Figure 14 is a plan view showing the 40 rock-shaft connections by which the spray is started and later cut off.

Figure 15 is a side elevation of the releasable latch shown in position to prevent the 45 closing of the valve of the sprayer.

The improvements claimed in the present application are in the nature of an improvement on, or a modification of, the invention set forth in my copending application, Serial No. 74,111, filed Dec. 8, 1925.

Before describing the details of the specific form of apparatus illustrating my invention shown in the drawings, I will indicate the general plan of operation in 55 order that such details may be more readily understood.

In the form illustrated, control is applied to a gyratory centrifugal of well known type embracing a separator basket *a*, surrounded 60 by a syrup-collecting curb or casing *c*, the basket being secured to the lower end of a gyratory rotary shaft *b*, whose upper portion *b'* is enlarged for the reception of rotary bearing elements, in accordance with 65 practice now well known. Secured to and

extending upwardly around the enlarged portion *b'* of the rotary basket-shaft, is a brake pulley *d* whose inside surface is frictionally engaged by a pair of interior brake shoes *g*, arranged to be expanded outward 70 into frictional engagement with the inside of the pulley. The centrifugal, comprising the separator basket, and its rotary shaft are suspended from a fixed suspension hanger *e*, secured to overhead supporting beams *f*, in 75 which hanger, the rotary basket-shaft is suspended in any suitable manner to permit gyration against yielding resistance, according to any suitable or well-known practice. As this mode of suspension is well known 80 in the art, and is not the subject of the present improvement, illustration and description of the details are omitted.

In the form illustrated, the centrifugal is driven through the overhead axially 85 aligned driving shaft *h* of an overhead electric motor, not shown herein, which is energized through a double switch to drive the centrifugal at low speed and at high speed during different stages in the cycle of opera- 90 tion.

Starting with the empty centrifugal at rest, the attendant throws the starting lever to low speed position and admits the load of wet sugar into the basket in the usual 95 manner, this loading requiring but a few seconds. On completing the loading the lever is then shifted to high speed position, thereby starting both the purging operation and the action of the automatic control 100 mechanism by which all subsequent operations are guided and controlled until the sugar is purified and ready to discharge.

The starting lever is returned to idle position by a coiled tension spring which yields 105 when the lever is manually advanced to low speed and to high speed positions, respectively, provision being made by an automatic latch or dog to lock the lever in high speed position to prevent its return until 110 released by the automatic control.

There are also connections leading from this main lever to the centrifugal brake shoes and to the switch knife, associated with the low speed and high speed motor circuits, whereby the brake, which is automatically set by a tension spring, is kept released or out of contact with the brake pulley, but is set when the lever is automatically released and returned to neutral 115 or idle position.

The automatic timer-control is started in operation by the throwing of the main lever to high speed position. The timer mechanism contains three separate and independently adjustable timing members, one of which starts the sprayer in action after a predetermined period of purging, the second of which stops the sprayer after any desired period of washing, and the third of 120 125 130

which releases the timer clutch and also releases the main starting lever after a pre-determined period of drying, and thereby causing the brake to be set and the motor switch to be opened in order to slow down the machine for discharging and stop it when the discharging is completed.

I will now describe the details of construction and arrangement by which these various operations, in their proper sequence and for any desired period of duration, are effected. The action of the starting and stopping lever, hereinafter referred to as the main lever, will best be understood by reference to Figures 1 to 6 inclusive of the drawings. As shown in Figures 1 and 2, there is secured to one of the overhead supporting beams f , to project out forwardly in front of the centrifugal, a forwardly extending web or bracket 3. On this bracket 3, together with a companion bracket 3^x , is mounted a fixed shaft 2, on the left hand end of which is mounted a main lever 1, for which it affords fulcral support. The upper end of this lever 1, extends above the fixed shaft 2, and carries an anchoring pin 8, to which is secured one end of a strong helical spring 9, coiled freely around the fixed shaft. The other end of this spring is anchored to a pin 10, mounted in a circumferentially adjustable anchoring block 10^a, which is secured to a reduced end 2^b of a fixed shaft to permit rotative adjustment of the block 10^a. A set screw 10^b is used to retain the anchoring block in its different positions of circumferential adjustment. The anchoring block is provided with spanner holes 10^c into which may be inserted the end of a rod or lever for securing the desired adjustment. The supporting rod or shaft 2 is splined in the bracket 3, as shown at 2^a, in Figure 2 and, consequently, by the rotative adjustment of the tension-adjusting member or block 10^a, any desired degree of torsional strength may be given to the spring 9, whose direction of torsional stress is indicated by the arrow in Figure 2, and tends to return the main lever to idle position.

The lower part of the supporting bracket 3 is provided with an arcuate runway formed between two arcuate ledges 3^a and 3^b, formed on the inner face of the bracket 3, the center of curvature being the center of the fulcral fixed shaft 2. In the upper ledge 3^a of this runway are bored two stop apertures 4 and 5 which determine, respectively, the positions of the main lever 1, the former for neutral position and the latter for low speed position. Co-operating with these stop apertures or stop shoulders 4 and 5, is a reciprocating plunger 6, mounted to slide radially or lengthwise of the lever 1, and to engage with either stop aperture 4 or 5, with which it may be placed in registry,

according to the position of the main lever. Forwardly of the stop recess 5 is a downwardly offset or projecting continuation of the upper ledge 3^a, as shown at 3^d. A pivoted hand grip 7, adjacent the handle of the main lever, is pivotally connected at 6^a, with the reciprocating stop plunger 6, so that it may be manually operated. It should be stated that in the position shown in Figure 2 the lever is in high speed position with the stop plunger 6, resting against the ledge 3^d and locked against return by a latch or dog 12, the details of which will presently be explained. In this figure the radial line marked r designates the position of the main lever when the apparatus is at rest and the brake is set against the brake pulley. The radial line n , in which the plunger 6 may be locked by the stop shoulder or recess 4, is the neutral position of the lever in which the brake is released, but the switch is not closed and no operation of any part of the apparatus occurs. The radial line s , shows the position in which the stop plunger 6 interlocks with the recess 5, at which position the motor switch knife is thrown into the low speed circuit when the operator is loading the machine, or it may be when the operator is discharging the machine after the spraying and drying operations have been finished and the machine has been slowed down.

Inasmuch as the main lever, in its high speed position as shown in Figure 2, is under heavy retractive tension from the helical spring 9, it must be locked in that position to prevent its return to idle position. This locking of the lever is accomplished by the action of an automatic dog or latch 12, of the form shown in Figures 2, 4 and 5. This dog is secured to a fore and aft rock-shaft 13, extending at right angles to the fixed shaft 2 forming the fulcral support of the main lever, the latch being transversely bored at its upper end to receive said rock-shaft or spindle 13, and having an offset inward portion or arcuate shoe 12^b laterally offset from the plane of the fulcral portion of the latch 12, with which it is connected by the short connecting right angle arm 12^c. The latch spindle 13 is mounted in the fixed supporting frame 3. As the latch or dog 12 is not intended to lock the main lever until it has passed by both the neutral position and the low speed position into high speed position, it is provided with a long arcuate shoe member 12^b, which engages an anti-friction roller 3^m, carried by the adjacent portion of the lever, as shown in Figure 6. The length of the arcuate shoe 12^b is sufficient to allow the lever to swing from idle to neutral and to low speed, without allowing the latch to swing in behind the stop roller until the lever has reached high speed position.

The latch spindle 13, as shown best in Figure 6, is provided with a spiral or torsion spring 14 whose torsional force is exerted in the direction of the arrow, Figure 6, to 5 throw the latch in behind the stop or roller 3^m, carried by the main lever. Secured to the latch spindle 13 is an arm 15, having a series of pin holes 15^a at different radial distances from the center to give the desired 10 degree of throw or movement to a connecting link 16, whose forked end 16^a is attached to this arm 15 by a connecting pin. The other end of this connecting link 16 is pivotally secured to a rock-arm 17^a, secured to 15 a rock-shaft which, at its farther end, is provided with a similar angularly disposed arm 17^b, into which is hooked the upper end of the timer-connecting rod 18 by which the timer mechanism is started in action when 20 the main lever is thrown to high speed position and by which, through the control of the timer, after predetermined periods, the main lever is released to return to idle position and the brake setting mechanism is allowed to act automatically to slow down and 25 stop the machine, all of which will be presently explained.

To prevent the automatic plunger 6 from engaging either of the stop recesses 4 and 30 5 on its automatic return to idle position, special controlling dogs or latches 6^c, in the form of toggles pivoted on the centers 6^a, and having their outer ends interconnected by a contractile spring 6^e, are employed. At their 35 inner ends these toggles have elongated slots engaging a projecting stud or pin 6^g, extending laterally from the plunger 6. When these toggle latches are swung about their pivotal centers, from one side of the center to the 40 other, they act, by means of the slotted engagement with the pin 6^g, to shift the plunger 6 in one direction or the other. In straight alignment across the plunger they are on the dead center. In the positions 45 shown in Figures 2 and 3, these latches act to retain the plunger 6 in its inactive or retracted position and, obviously, if swung to the other side of the dead center they will equally maintain it in its active position to 50 engage either the recess 4 or the recess 5, thereby locking the lever 1 in either neutral or low speed position. It will be observed that the runway between the ledges 3^a and 3^b, afford a passage or channel through 55 which the pin controlling these latches or dogs may travel as the lever 1 swings to and fro, and also that the right hand end portion of the lower ledge 3^b, as shown at 3^c, is flared or dropped away from the circular arc 3^b, to 60 form a cam-like surface which will engage the pin 6^g, on the plunger as the lever swings to the left and force the toggles slightly beyond the dead-center position so that they are exercising an upward thrust 65 on the plunger. This does not occur until

after the plunger, on the return movement of the lever 1, has passed the socket or recess 4 and, consequently, while the plunger can not move far beyond the dead center position, it is kept under tension so that when the plunger is manually thrown to the right from the at-rest position *r*, it will spring into the recess 4 automatically from which it may be withdrawn by the hand-grip 7 when the operator desires to shift the lever 75 to low speed position on the line *l*.

The reason for providing a neutral position, in addition to the low speed and high speed and inactive position of the lever, is to release the brake and allow the centrifugal 80 to run freely under its own momentum in case the operator finds it desirable to do so for any reason, such as prolonging the unloading period. This neutral position will also be useful when the apparatus is being 85 washed down by the operator for cleaning purposes.

I will now describe the connections leading from the main lever 1, to the brake mechanism and the double circuit motor switch, 90 these being best shown in plan view, Figure 7. On the inside face of the main lever 1 is secured a stud or post 20, carrying a pivotal block 21, to which is pivotally connected the forked end 22^a of a rearwardly extending 95 connecting rod 22, having, at its rear end, a fork 22^b, connected to a pivot-block 23^a on the end of an arm 23, secured to a vertical rock-shaft 24, depending from the fixed hanger *e* between the two adjacent free ends 100 of the brake shoes *g* to form a fulcral support for the toggle links 26, 26^a, which are pivotally connected to a disk or collar 25, fulcrumed on the vertical spindle 24.

It will be understood that when the main 105 lever 1 moves to its rearmost or idle position at *r*, the brake-actuating arm 23 is rotated in a clockwise direction to powerfully expand the brake toggles 26, 26^a and force the brake shoes *g*, which are fulcrumed on a spindle 110 at *g'*, carried by the hanger, into frictional or braking engagement with the interior of the brake pulley *d*, which is secured to the enlarged upper end portion *b'* of the basket-shaft. When the brake lever is moved forward from idle position it acts to immediately release and unseat the brake to leave the centrifugal free to rotate both in neutral and in the two-speed driving positions.

Fulcrumed on the brake spindle 24 is arm 27 which is connected, by means of a link 27^a, adjustable as to length by nuts, 27^b, with the electric switch knife 28 which is provided with two separate terminals 28^a for the low speed and 28^b for the high speed circuits of the driving motor. The low speed switch pole 28^a is extended out beyond the radial line of the high speed switch 28^b, the parts being so arranged and proportioned that 130

when the main lever is moved to low speed position, indicated by radial line s , Figure 2, the switch knife 28 will be engaged with the low speed terminal 28^a to close the low speed circuit. On further forward swinging of the lever 1 to high speed position, the switch knife 28 will be moved further inward to engage also the high speed terminal 28^b. The terminal 28^c is common to both circuits. In neutral position of the main lever the switch is wide open, extending off to the right away from both switch terminals. It will, therefore, be seen that both the centrifugal brake mechanism and the motor-controlling switch are actuated through a common actuating member so that the brake must always be open when the switch is closed, and the brake may or may not be set according to its adjustment to idle or neutral position when the switch is open. The adjustment of the heavy lever-actuating spring 9 makes it possible to get any desired degree of tension and, consequently, any desired degree of braking action so as to determine with precision the rate of slowing down of the machine from high speed, preparatory to discharging the purified sugar.

I will now describe the construction and operation of the automatic controlling mechanism by which the time-control and regulation of each automatically-controlled operation in the cycle is effected.

For convenience the timer mechanism σ is mounted upon the sprayer m at the right hand side of the machine. The actuating drive for both the timer and the sprayer, as shown in Figure 1, comprises a horizontal driving pulley 30, carried at the end of a swinging arm 31, which is fulcrumed above the timer σ , and which is normally kept pressed against the exterior of the basket-shaft b by a contractile spring 31^a (Fig. 13). This arm is hollow and carries an interior horizontal transmission shaft 32, having beveled gear connection at its outer end with the pulley 30, and at its inner end with a vertical driving shaft 33, which extends down into the timer and carries a cam 51 for oscillating the sprayer-actuating arm 50 which is supported upon said cam by a roller 50^a.

As the details of construction of the sprayer are not claimed herein as part of this invention, it will suffice, for present purposes, to state that the sprayer construction is very similar to that shown in Letters Patent granted me May 18, 1926 No. 1,585,608, except that the sprayer contains no timing mechanism as in that patent, but is under the control of the unified timer that exerts a common control over the operations described, except loading and unloading. It will be understood that the vertical shaft 33, which drives both the timer mechanism and the sprayer is constantly running so long

as the centrifugal is running since it is in constant drive connection with the basket-shaft; hence the cam 51, for oscillating the arm 50 of the sprayer, is always in operation when the machine is in operation, but the water supply, passing in through the filter 52, to the valve casing 53, is only turned on when the valve stem 56 is raised to open the valve. Furthermore, in this case the spray-nozzle itself is in the form of a vertically reciprocating pipe 54, having a connecting nipple at 54^a, for a flexible connecting hose 54^b which is in communication with the conduit 53 leading from the valve casing 53, this flexible connection making it possible to give any desired reciprocation to the spray-pipe 54, which is mounted in bearings 55^a of an adjustable bracket 55, secured to the sprayer casing m , by a screw and slot connection at 55^c, as shown in Figure 8, by which the pipe may be adjusted inwardly or outwardly inside of the centrifugal basket. The reciprocating spray pipe is provided with a horizontal pin 55^d, which rests upon the outer end of the spray-actuating arm 50, to give the desired degree of reciprocation to the spray pipe which is perforated on the side toward the surrounding sugar wall, as indicated in Figure 1, to direct a fine spray against the adjacent inside wall of the sugar, the spray openings being distributed to deliver the proper quantity of water to different levels of the sugar wall.

Since the oscillation of the spray-pipe or nozzle continues so long as the centrifugal is running, it is necessary to provide only for the turning on of the spray at the proper stage in the cycle of the centrifugal operation and its shutting off after a predetermined interval. This is effected through mechanism controlled by the timer device mounted on top of the sprayer casing m . A rock-shaft 57 (Figs. 8, 9 and 14), mounted in the sprayer casing, carries an arm 57^a, normally pulled in the clockwise direction (Fig. 9) by a tension spring 57^b, anchored to a tension adjustment screw 57^c. This rock-shaft also carries an arm 56^a, engaging an eye or loop in the upper end of the valve 56 so that the tension of the spring 57^b presses the valve stem downward to keep the valve closed, while an upward movement of the arm 56^a acts to open the valve by raising the valve stem. On the opposite side of the shaft 57 projects a forked arm 58, having pivotal connection with a vertical latch or catch 60 whose lower end is connected by means of a contractile spring 58^b, carried by a stud or screw 58^a secured to the hub of the arm 58 so that the tension of the spring tends to draw in the lower end of the latch 60 and yieldingly move outward the upper end of the latch. The latch 60 is formed, near its upper end, with a shoulder or abutment 60^a, adapted to thrust against the underside of a

fixed stop lug or bar 61, carried by the frame of the timer *o*.

This latch, when the valve is closed by the spring 57^b, has its stop shoulder 60^a normally spaced some distance above the fixed stop 61. Near its upper end the latch carries a pivotal dog or finger 60^b, adapted to be engaged by a projection 45^d on a rotatable timer ring 45, of the timer mechanism presently to be described, as shown in Figures 9 and 15. This latch 60^b is pivoted to permit swinging upward from its horizontal position to allow the return of the timing ring swell, but can not swing downward below the horizontal; hence the downward movement of the swell or projection 45^d serves to depress or push down the latch 60 so that, when the shoulder 60^a comes below the level of the stop 61, the contractile spring 58^b swings the latch 60 into stop engagement with the fixed stop 61, in which position the valve stem is raised to open the valve and allow the sprayer to function.

Further rotation of the timer-shaft acts to release the latch from its stop position and allow it to return to uppermost position to let the valve close. This is accomplished by means of a bell-crank arm 62, whose horizontal member projects out to be engaged and depressed by the revolving timer, and whose vertical arm carries a projecting pin 62^a, adapted to strike against the outside face of the latch 60 and force the latch inwardly, thereby releasing the latch shoulder 60^a from engagement with the fixed stop 61. The latch being so released no longer prevents the spring 57^b from actuating the rock-shaft 57 to shut off the water from the sprayer and nozzle.

I will now describe the details of the timer mechanism by which the various movements are controlled. Alongside of the shaft 33, driven from its connection with the centrifugal machine-shaft, is a vertical counter-shaft 34, which has driving connection from the shaft 33 through speed-reducing pinions 33^a, 34^a (Fig. 8). The counter-shaft 34 also carries a worm 34^b that intermeshes with a worm 41^b that is loosely mounted on the horizontal timer shaft 43, (Fig. 11). Along one end of this timer shaft 43 is mounted a spanner head or nut 43^a, to which is pinned a spiral spring 43^b, the outer end of which spring is anchored to a fixed pin 43^c, on the timer casing *o*, which permits adjustment of the spring tension as the nut is turned one way or the other. The other end of the timer-shaft carries a circular head 44 formed with three peripheral spaces to receive three timer rings 45, 46 and 47, each of which may be independently adjusted circumferentially of the timer head. The respective rings carry peripheral swells or projections 45^d, 46^d and

47^d. The three circumferentially adjustable timer rings are mounted on the space between the inner face-plate 48^b and the outer face-plate 48, which are secured to opposite faces of the timer head 44. The outer plate 48 carries three bosses 48^a, at different distances from the center, in which are mounted spring plungers 45^e, 46^e and 47^e, to engage, respectively one of an annular series of holes 45^b, 46^b and 47^b, formed in the respective rings so that, when the plunger for any ring is retracted, the ring may be turned to any desired circumferential position of adjustment and the plunger released to allow it to spring into locking engagement in one of the transverse holes of its ring to maintain it in its adjusted position. The peripheral face of each timer ring is provided with several radial holes or sockets 45^a, for the insertion of a spanner wrench or rod for facilitating the adjustment of the different rings.

As it is desired that the timer-shaft shall not be acting all the time the centrifugal is running but only while the centrifugal is running at high speed, its driving worm-gear 41^b is loose on the shaft and is operatively connected therewith by means of a slidable clutch pulley 41, which is splined to the shaft 43. Except at high speed, this spline clutch is out of engagement with the companion clutch 41^a, on the adjacent face of the worm-gear 41^b. The control of this clutch is best shown in Figures 10 to 13. Above the timer-shaft and at right angles thereto is mounted a clutch-shaft or spindle 40, having splined to its outer end a doubled arm or yoke-like lever 19^b, carrying opposed set-screws 19^c in line with an intermediate lever or arm 19 which is loosely fulcrumed on the clutch spindle 40. One end of this arm 19 is pivotally connected by pivot-pin 18^a with the connecting link 18, which extends upwardly to the rock-shaft 17, which is interconnected with the main lever 1, as above described. The other end of the lever 19 projects across the intermediate timer-ring 46, in position to be engaged by the swell or projection 46^d, on its intermediate ring. This constitutes the knock-off movement by which the connecting link 18 is pulled downward by the timer mechanism so as to release the dog 12 that holds the main lever 1 in high speed position, and by this downward pull and release the main lever is allowed to swing back under its torsion spring to idle position at the same time setting the brake.

It will be observed that the knock-off arm 19, instead of being connected directly to the clutch spindle 40, upon which it is loosely mounted, is connected operatively therewith through the medium of the splined arm 19^b, by engagement with the set screws 19^c. The object of this arrangement is to provide a

slight lost motion at this point to prevent binding of the mechanism which might occur if the action of the mechanism should be too closely co-ordinated.

- 5 The upward movement of the link 18, as above described, is effected only when the main lever is thrown to high speed position. This rocks the clutch spindle 40 in a counter-clockwise direction, according to the showing in Figure 10, or in a clockwise direction, according to the showing in Figure 11, thus throwing the clutch 41 into intermeshing engagement with its companion clutch 41^a, fastened to the worm gear 41^b, which is constantly driven so long as the centrifugal is running by reason of the speed-reducing pinions 33^a, 34^a, and the worm-drive connection. The rotation of the timer-shaft is comparatively slow. Having reference to 20 Figure 9, the swell 45^a, on the outer timer-ring, after a predetermined arc of rotation, according to its adjustment, engages the dog 60^b, forcing down the latch 60 into engagement with its stop member 61, so that the sprayer-valve is opened and maintained in opened position until the swell 47^a, on the innermost ring 47, engages the trip lever 62 and disengages the latch 60 from stop 61 to allow the valve to close under the tension of 25 spring 57^b.

It will be understood that the return spring 48^b of the timer, is being wound up under gradually increasing tension as the timer revolves during its active period.

- 5 When the clutch is released or knocked off, the spring acts to return the timer-shaft to zero or starting position against a stop, as best shown in Figure 10, which comprises a pivotal stop-dog 65 mounted on the timer-frame or casing σ , having its outer end projecting outward, and carrying a buffer 65^a of rubber or the like to engage a co-operating arm 66, projecting from and secured to the hub of the timer-head. The stop dog 45 65 is pivoted instead of being rigidly secured to the casing, in order to permit the free revolution of the head in a direction to wind up the spring. As the rear face of the projecting end of the stop-dog 65 is beveled, the dog easily yields when the stop abutment 66 strikes it from the rear to allow the stop abutment to pass by. The gravity of the longer arm of the dog 65 tends to keep it in horizontal position since its inner end 55 abuts against a fixed stop or rib 67 on the casing.

- Obviously, the circumferential spacing between the swells 45^a and 47^a will determine the duration of the period of spraying, and 60 it will be equally clear that the circumferential adjustment of the member 45^a determines the duration of the spraying period. The circumferential distance of the member 45^a, from the dog 60^a, in its elevated position

from the starting or initial point of the 65 timer, determines the duration of the purging period following the setting of the main lever to high speed position.

What I claim is:

1. In a centrifugal apparatus, the combination with a centrifugal and its driving means, of a starting lever adapted to be shifted to normal operative position at the will of the operator, a sprayer, a controller set in operation by the movement of said lever to operative position, said controller having three adjustable elements acting respectively to start and to stop the sprayer after predetermined but variable intervals, and to shift the lever to idle position to allow the centrifugal to stop. 70

2. A starting and stopping mechanism for a centrifugal embracing a pivotal lever movable to starting position against spring tension, an interconnected brake actuated by spring tension to be set to brake the centrifugal when the lever returns to idle position, means for retaining the lever in different positions to impart different speeds of rotation to the centrifugal without allowing the brake to set at either speed, and means for automatically releasing the lever from normal operative position after a predetermined period to stop the centrifugal. 85

3. Automatically releasable starting means for a centrifugal embracing in association with two speed driving means, a pivotal lever, lever-positioning and holding means by which the lever is retained at one or more intermediate positions between its extreme position of idleness and of full speed, and means whereby the lever, when released from its full speed position, is permitted to return to idle positions without being arrested in any intermediate position. 95

4. Automatically releasable starting mechanism for a centrifugal embracing in combination a pivotal starting lever movable from idle to full speed positions against yielding resistance tending to return it to idle position, a detent carried by said lever and arranged to engage adjacent stop shoulders in the adjacent frame to hold it in some intermediate position, means for automatically engaging said detent with one of said stop shoulders as the lever is moved toward starting position, said means also acting to prevent said detent from engaging either stop shoulder on its return movement to idle position. 100

5. In an automatically controlled centrifugal apparatus, the combination of a starting element movable by hand from idle position to normal operative position against yielding resistance tending to return it to idle position, a brake and a motor switch, operatively interconnected with said starting element, to be moved to idle position and to 115

- circuit-closing position respectively by the movement of the starting element from idle to operative position, means for releasably locking the starting element against return 5 to idle position, and means driven by the centrifugal for releasing said locking means after a predetermined period.
6. In an automatically controlled centrifugal apparatus, the combination of a starting element adapted to be moved from idle to operative position against a yielding and adjustable resistance tending to return said starting element to idle position, a brake operatively connected with said lever to be set 10 to braking position when the starting element is moved to idle position and to be released when the starting element is moved away from idle position, a motor switch arranged to close in succession low speed and 15 high speed motor energizing circuits by the movement of the starting element and timing means arranged to release the lever from high speed position.
7. In a motor driven centrifugal apparatus, the combination of a pivotal starting lever movable manually to operative position, a detent for releasably locking it in said position, a brake, a switch for closing low speed and high speed circuits of the driving 20 motor, a common spring acting to move said lever to idle position and set said spring and open said switch, and timer means connected with said detent to act after a predetermined and variable period to release said detent and 25 allow said spring to open the switch and set the brake.
8. In an automatically controlled centrifugal apparatus, the combination with a centrifugal, of means for manually starting and 30 automatically stopping the centrifugal, a sprayer, a rotary timing controller driven by a releasable connection with the centrifugal, said timer having circumferentially adjustable members for turning on the spray after 35 a predetermined interval following the starting of the centrifugal, for stopping the spray and for stopping the centrifugal and releasing its own driving connection with the centrifugal, respectively, and means for returning 40 the timing controller to initial position when its operative connection with the centrifugal is released.
9. In combination with a sugar purifying centrifugal and its associated driving motor and brake, a starting lever movable at will 45 against the resistance of a return spring and having operative connections with the brake and with the starting switch of the motor, a sprayer, a timer for starting and stopping 50 the sprayer, a timer starting element acting to retain the aforesaid starting lever in its operative position, said timer starting element being itself releasable by the action of the timer to stop the centrifugal at a prede- 55 termined interval after the sprayer has been stopped.
10. In combination with a sugar purifying centrifugal and associated driving motor and brake, a two-speed motor controlling switch combined with brake-actuating means, both 60 movable to centrifugal operating position against resistance of a return spring, a sprayer, a timer controlling the starting and stopping of the sprayer while the centrifugal is running, timer starting means acting to 65 prevent the return of the switch and brake to centrifugal non-operating position until the timer starting means is itself released by the timer.
11. In combination with a sugar purifying 70 centrifugal and associated two-speed driving means and brake, a starting element movable by the operator against resistance of a return spring to first and second positions in 75 succession, said starting element having connection with the brake to unset the brake before the starting element reaches either speed driving position, a sprayer, a timer controlling the starting and stopping of the sprayer at predetermined intervals after 80 starting the centrifugal, a timer starting element arranged to prevent the return spring from acting to cause the stopping of the centrifugal and being itself released by the timer after the sprayer has stopped to allow 85 the stopping of the centrifugal.
12. In combination with a sugar purifying 85 centrifugal and associated driving and braking means, a starting element having actuating connection with said driving means and 90 with said brake and movable to brake unsetting position before reaching operative driving position, means acting to return the starting element from normal centrifugal operating position to initial non-operating and 95 brake setting position, a sprayer, a sprayer controlling timer and means for starting said timer in action when the centrifugal starting element reaches normal operating position, said timer starting element acting 100 also to prevent the return of said starting element to non-operating position until the timer starting element is itself released.
13. In combination with a sugar purifying 105 centrifugal and associated driving motor and brake, a starting member operatively combined with the motor switch and with the brake and movable to centrifugal operating position, a sprayer, timing means for 110 starting and stopping the sprayer at predetermined intervals during the operation of the centrifugal, means rendered operative by the timing means for returning the starting member to centrifugal stopping position, and means released by the timer for restoring 115 the timer to its initial position.
14. In combination with a sugar purifying 120 centrifugal and an associated driving motor

and starting switch, means for returning the switch to open circuit position, a sprayer, clutch driven timing means for starting and stopping the sprayer at predetermined intervals following the starting of the centrifugal, means for shifting said clutch to operative driving position when the switch is moved to circuit closing position, and means controlled by the timer for releasing said clutch from driving relation. ¹⁰ In witness whereof, I have subscribed the above specification.
